UNITED STATES PATENT OFFICE.

CHARLES REIER, OF NEW YORK, N. Y., ASSIGNOR TO BUILDING IMPROVEMENT CO.,
OF NEW YORK, N. Y., A CORPORATION OF NEW YORK.

FLOOR AND CEILING CONSTRUCTION.

1,109,785.

Specification of Letters Patent.

Patented Sept. 8, 1914.

Application filed February 6, 1912. Serial No. 675,795.

To all whom it may concern:

Be it known that I, CHARLES REIER, a citizen of the United States, and resident of the borough of the Bronx, city, county, and State of New York, have invented certain new and useful Improvements in Floor and Ceiling Construction, of which the following is a specification.

My invention relates to floor and ceiling constructions and more particularly to those commonly known as reinforced concrete floors or ceilings in which a number of open ended units or blocks are incorporated in rows in such a manner as to form parallel channels for the accommodation of the usual reinforcing rods.

The object of the invention is to provide simple and efficient units or blocks which may be readily incorporated in the construction in the desired correlation to each other and which are easily and cheaply manufactured.

Other objects of the invention will appear from the description hereinafter and the features of novelty will be pointed out in the appended claims.

Reference is to be had to the accompanying drawings in which—

Figure 1 is an end elevation of my improved unit or block; Fig. 2 is a plan view thereof; Fig. 3 is a cross-section of a portion of a floor or ceiling constructed according to my invention; Fig. 4 is a plan view thereof and Fig. 5 is an end view of a slightly different form of unit or block.

The blocks or units constructed according to my invention each comprise a top 5 from the opposite longitudinal edges of which sides 6 and 7 extend so as to form, with said top 5 an inverted substantially U-shaped body having its opposite ends open and being normally open at the bottom, as shown in Fig. 1. A preferably flat member 8 projects from one edge of the side 6 in a direction substantially parallel with that in which the top 5 extends and is preferably, though not necessarily, provided at its free edge with a flange 9 as shown in Figs. 1 and 3. The units or blocks may be made of any suitable material such as wire-screening or mesh, metal, wood, concrete or the like, terra cotta or in fact any other material suitable for the intended purposes. Thus if the material used is capable of manipulation it

may be bent or shaped so as to form the elements 5, 6, 7, 8 and 9, or these elements may be separate parts secured together in any suitable manner to form an integral structure of the desired shape, or said units or blocks may be molded or otherwise constructed as may be found convenient.

In constructing a floor and ceiling according to the present invention the blocks or units are first set up on the usual centering or scaffold for instance in the following manner: The first unit or block is placed upon the scaffold with its side 7 in engagement for instance with one of the side walls of the building and its one open end adjacent to the one end wall thereof after which the second unit is similarly set alongside of the first and so that the member 8 of the first block extends beneath the side 7 of the second block and the flange 9 of said first block is in engagement with the inner surface of the side 6 of the second block. Similarly the third block is set up alongside of the second block and so on until finally the flange 9 of the last block in this row is adjacent to the opposite side wall of the building. In order to complete this row a substantially U-shaped unit composed of a top 5^a and sides 6^a and 7^a may be placed so that the free edge of its side 7^a rests on the member 8 of the last block of this row and its side 6^a in engagement with the flange 9 of said last block as clearly shown in Fig. 3. A similar U-shaped unit may be located in the first block of the row in such a manner that the sides 6^a and 7^a extend upwardly in engagement with the sides 6 and 7 and the top 5^a bridges the space therebetween and now becomes the bottom of the first block. The next row of units is now similarly set up with the one open end of each block body engaging and alining with the one open end of each block body of the first row and so on until finally the necessary number of rows have been set up to cover the area of the intended floor or ceiling. In this condition it will be seen that the members 8 of one block extend beneath and form a bottom for the inverted substantially U-shaped body of the adjacent block, and by contacting with the inner surfaces of the sides 6, 6^a serve to space the sides 6 and 7 of adjacent blocks apart to form channels 10 extending substantially parallel to

each other as clearly shown in Fig. 4. The usual reinforcing rods 11 are now placed in the channels 10 so as to extend lengthwise thereof and in the described construction 5 with their ends properly supported in the opposite end walls of the building in the usual manner, which end walls also serve to close the one open end of each unit in the first and last row. Concrete or other coalescent material 12 is now introduced into 10 the channels 10 so as to surround the rods 11 and completely fill said channels and in some cases to also cover the tops 5 and 5^a of the units. If the units are constructed of 15 wire mesh some of this coalescent material will work its way into the interstices of the sides 6, 6^a and flanges 9 and when set or hardened will form keys or projections to prevent separation of the units and interlock them at these points. After the coalescent material has set the centering may be 20 removed thus leaving a perfect monolithic floor or ceiling in which the lower or exposed surfaces of the members 8, and 5^a if 25 used, serve as supports for plaster or any other material adapted to comprise the finished ceiling. In the finished structure the coalescent material in the channels 10 form load sustaining girders of great 30 strength while the units themselves act as fillers thus reducing the dead weight of the floor or ceiling and adding to its strength while at the same time providing air spaces between the upper and lower surfaces of the 35 structure.

In order to save coalescent material and to 40 secure a more perfect arch construction the tops 5 or 5^a may be made to incline upwardly toward the center and the sides 6 and 7 may converge downwardly toward 45 each other in the finished structure as shown in Fig. 5. This arch construction is capable of resisting heavy strains and in addition reduces the amount of coalescent material necessary to complete the structure.

The width of the channels 10 may be adjusted as desired by simply increasing or diminishing the distance between the free end of the members 8 of each unit and the 50 side wall 6 as will be readily apparent from an inspection of the drawings.

If desired the flanges 9 may be omitted in which case the free edge of each member 8 will simply abut against the inner surface of 55 each side 6 or 6^a to space the sides 6, 6^a and 7 of adjacent blocks apart.

If the units or blocks are made of a material capable of being manipulated, they may be shipped in flat sheets of the desired dimensions and shaped to the desired form 60 just prior to use, so that in this case a maximum number of units may be shipped in a minimum amount of space. It will readily be seen that my improved blocks or 65 units may be cheaply and quickly manufac-

tured and easily and quickly set up for use by unskilled labor, and will at the same time produce a floor or ceiling of great strength and minimum dead weight.

Instead of using a U-shaped unit to complete the first block in a row as described hereinbefore, the top 5 and side of the first unit may simply be cut away and a unit consisting only of the side 6 and member 8 thus produced. This unit may be set on the centering with the side 6 spaced from the wall of the building in which case the space between the wall and side 6 would be filled with coalescent material or the said unit might be positioned with the side 6 in engagement 75 with the wall of the building.

In order to reduce the amount of temporary scaffolding or centering needed in constructing the floor or ceiling to a minimum, wire loops 11^a may be passed about the 80 reinforcing rods 11 at intervals and passed through the members 8 so that said members will be suspended from said bars at the points where the loops 11^a are located. These loops will prevent the members 8 85 from sagging as the coalescent material is introduced and during the setting of said material in the same way as does the temporary scaffolding. In other words if the loops are not used, it is necessary to support the members 8 from below at all points by means of centering while if the loops are used a great part of this centering may be omitted as will be readily apparent.

Various changes in the specific forms 90 shown and described may be made within the scope of the claims without departing from the spirit of my invention.

I claim:

1. A block or unit comprising a top wall, 105 side walls depending from said top wall at opposite edges thereof to form therewith an inverted U-shaped element and a bottom forming member extending outwardly from one of said side walls, the distance between 110 said side wall and the free edge of said bottom forming member being greater than the distance between the two side walls.

2. A block or unit comprising a top wall, 115 side walls depending from said top wall at opposite edges thereof to form therewith an inverted U-shaped element, a bottom forming member extending outwardly from one of said side walls and a flange projecting upwardly from said bottom forming member at the free edge thereof, the distance between said flange and the one side wall being greater than the distance between the two side walls.

3. In a floor or ceiling construction, a plurality of units comprising an inverted substantially U-shaped body having open ends and being open at the bottom, said units being arranged adjacent to each other and each having a portion extending beneath the 125 130

inverted U-shaped body of an adjacent unit across the axis thereof to form a bottom for said adjacent inverted U-shaped body and a coalescent material located between said 5 blocks.

4. In a floor or ceiling construction, a plurality of units having bodies open at the bottom and arranged adjacent to each other, said units having portions adapted to form 10 opposite walls of a channel and another laterally extending portion adapted to extend beneath the body of an adjacent unit across the axis thereof to form a bottom for said body and also to form the bottom of 15 said channel and a coalescent material in said channel.

5. In a floor or ceiling construction, a plurality of units, arranged adjacent to each other and having top walls and side walls 20 depending therefrom, each unit having a bottom wall extending beneath the one side wall of an adjacent unit into engagement with the opposite side wall thereof to form the bottom of said adjacent unit and to 25 space portions of adjacent blocks to form the opposite walls of a channel, said bottom wall itself forming the bottom of said channel and a coalescent material in said channel.

6. In a floor or ceiling construction, a plurality of units arranged adjacent to each other and having top walls and side walls depending therefrom, each unit having a 30

bottom wall extending beneath the one side wall of an adjacent unit to close the bottom thereof, a flange projecting from said bottom wall and engaging the opposite side wall of said adjacent unit, said bottom wall being arranged to space portions of adjacent blocks to form opposite walls of a channel and to itself form a bottom for said channel, a reinforcing rod extending lengthwise of said channel and a coalescent material in said channel covering said reinforcing rod. 35

7. In a floor or ceiling construction, a plurality of units having bodies open at the 40 ends and bottom, said units being arranged in adjacent rows with their open ends in engagement, a projecting portion on each unit extending beneath and across the bottom of the body of an adjacent unit to close 45 and form a bottom for the same and to space portions of adjacent units apart to form parallel and continuous channels, reinforcing rods extending lengthwise of said 50 channels and a coalescent material in said 55 channels covering said reinforcing rods.

In testimony whereof I have hereunto set my hand in the presence of two subscribing witnesses.

CHARLES REIER.
